Serial No. 574,101

3 Claims. (Cl. 101—288)

This invention relates to a printing machine of that character which is capable of printing a continuous strip or web having strings attached to sections thereof, so that when the sections are severed from the strip, printed tags are produced having a string attached to each one.

The invention is an improvement upon the printing machine illustrated in the patent to Albert H. Ray No. 1,318,108 granted October 7, 1919, and the object of the invention is to provide for the web or strip a guide of novel construction, positive and efficient in action, inexpensive and not liable to be rendered inoperative in transit or in the place where the machine is used, as will be described.

The particular features of the invention will be pointed out in the claims at the end of this specification.

In the drawings illustrating the preferred embodiment of the invention, Fig. 1 is a vertical sectional view through the improved machine; Fig. 2 is an end elevation viewed from the right-hand side of the machine shown in Fig. 1; Fig. 3 is a detail in perspective of the new string guiding mechanism; and Fig. 4 is a sectional plan of a portion of the machine illustrating the same.

In general, the present invention contemplates a machine of the type illustrated in the Ray Patent No. 1,318,108 above referred to, which is designed to print a continuous strip or web of paper or other material having strings attached to sections thereof, so that when the sections are severed from the strip, printed tags are produced having a string attached to each tag.

As illustrated in the drawings, and as shown in said Ray patent, the machine comprises essentially a stationary platen *a* and a reciprocating printing member *b* cooperating therewith. The reciprocating printing member *b* comprises a chase 15 containing type 16, and provision is made for reciprocating the printing member *b* at timed intervals in the operation of the machine from a cam 26 having a cam path 25 through suitable connections, as shown in the above mentioned Ray patent including a plunger 17 arranged to slide in a suitable guide 18. Provision is also made for supplying ink to the type and the inking mechanism may and preferably will comprise that illustrated in the printing machine disclosed in the above-mentioned Ray patent including one or more ink rollers 31 carried upon an endless carrier 34 and arranged to be supplied with ink from an inking disk 40 over which the rollers pass during the traverse of the chain around its supporting sprockets.

Provision is made, as in the above-mentioned Ray patent, for feeding the web or strip of tag forming material through the machine, and as illustrated in Fig. 1, the material is drawn from a supply roll over a bed plate 90 by the cooperation of pins 91 with the strip. The pins 91 project upwardly from a plate 190 forming a part of a carriage 92 and are preferably arranged in rows near the opposite sides of the carriage and spaced apart a distance substantially equal to the width of a section of the web to be printed upon, and as shown in the above-mentioned Ray patent the feed pins 91 are designed to engage the strip or web between adjacent sections. Provision is made for elevating the pin plate 190 to render the pins operative to advance the web, and this mechanism may comprise that shown in the above-mentioned Ray patent including a cam 93 cooperating with a bar 95 connected through posts 96 to the pin plate 190, as shown in Fig. 1. Near the end of the forward movement of the carriage 92 the cam 93 permits the plate 190 to drop by gravity assisted by the spring 104 to withdraw the feed pins from the notches in the edge of the strip to be printed upon. The carriage 92 may and preferably will be reciprocated from a crank 87 and connecting rod 86, as shown.

Provision is also preferably made for severing the individual printed sections of the web by a cutting mechanism which may comprise a movable cutter or knife 63 cooperating with the stationary cutter 110, and the movable cutter 63 may be operated from the cam 25 through suitable connections, not shown, but which are clearly illustrated and described in the above-mentioned Ray patent.

The machine as thus far described may and preferably will comprise the machine illustrated in the above-mentioned Ray patent and to which reference may be made for more detailed description thereof.

In the operation of the machine, the web to be printed upon is drawn from the roll and first passes between the horizontal upper surface of a guide member 155 projecting from the right-hand side of the frame of the machine, as viewed in Fig. 1, and a cover plate 152 mounted upon and supported by an arm 153 pivoted at 154 upon the frame of the machine. The cover plate 152 is maintained in operative position spaced slightly above the bed plate 90 and has a portion thereof extended beyond the bed plate to cooperate with the guide member 155 and form a guideway for the web or strip of tags. A stop 156 as illustrated in Fig. 2 positions the arm 153 and cover plate 152

with relation to the bed plate 90 and the guide member 155. The parts are arranged so that sufficient space is left between the cover plate and the upper surface of the bed plate to permit the web to freely pass therebetween and to be drawn forwardly in the manner above described by the pins 91 forming a part of the carriage at each forward advance of the carriage. The bed plate 90 of the machine is provided with the usual slots, as above described, through which the pins may project into the web engaging position, and is further provided with a channel as described in the patent referred to, which is arranged to co-operate with a channel 151 formed in the under surface of the cover plate 152 to provide ample space into which the loops of strings on the web may pass during the progress of the strip through the machine, thereby enabling the strings to be removed from the path of the reciprocating printing member and to enable the strung strip or web to be printed without interference of the strings.

In order to assist in guiding the strings into the channel, I provide the forward end of both the cover plate 152 and the underlying guide member 155 with an inclined or angularly disposed edge 160, as shown in Figs. 3 and 4, arranged in such position as to engage the strings and guide them into the channel 151. The hinged cover plate 152 enables convenient access to be had to the underlying web, so that in the event that any of the strings do not pass into the channel, the fault may be easily corrected by swinging back the cover plate and exposing the channel in the bed plate and also the guideway beyond the end of the bed plate, thus enabling the machine to be operated with minimum delay.

The present construction of string guiding mechanism, including the guide member 155 and the cover plate 152, enables a superior control to be had of the web during the period in its travel into the machine when the strings are being guided into the channel. The web is caused to travel in a horizontal plane while the inclined edge portion 160 of the plates 152, 155 are operating to guide the strings down into a position where they will hang over the edge of the web or strip and pass through the channel 151 in the manner above described, thus insuring a most efficient operation of the guiding mechanism. The construction of string guiding mechanism is simple and may be economically manufactured.

It will be observed that the cover plate 152 projects beyond the bed plate a substantial distance, and that this projecting portion is integral with the cover plate and forms a rigid and substantial upper guide member having an inclined front end which forms a strong and rigid member for deflecting the strings toward the channels in the bed plate and cover plate.

The lower guide member 155 is also of rigid construction and this rigid construction of the upper and lower guide and deflecting members resists disturbance of the relation of the members by blows or jars in assembling and transportation of the machine, and also when in use, thereby avoiding loss of time in the use of the machine and expense in placing the guide members in operative condition.

While the preferred embodiment of the invention has been herein illustrated and described, it will be understood that the invention may be embodied in other forms within the scope of the following claims.

Having thus described the invention, what is claimed is:—

1. In a printing machine of the character described, in combination, a bed plate over which a strip or web strung with strings is fed, a cover plate for said bed plate having an end portion projecting beyond the end of said bed plate and provided with an angular forward edge for guiding strings during the passage of the web thereunder and toward said bed plate.

2. In a printing machine of the character described, in combination, a bed plate over which a strip or web strung with strings is fed, a cover plate for said bed plate having a rigid end portion projecting beyond said bed plate and provided with an inclined front edge, and a rigid guiding member below the projecting end of said cover plate and provided with an inclined front edge registering with the inclined front edge of the cover plate.

3. In a printing machine of the character described, in combination, a bed plate over which a strip or web strung with strings is fed, a rigid guide member having an inclined front edge, and a rigid cover plate co-operating with said bed plate and said rigid guide member and having an inclined front edge registering with the inclined front edge of said guide member.
